UNITED STATES PATENT OFFICE

ISAAC W. BROWN, OF EL DORADO SPRINGS, MISSOURI

BLIND FOR BRIDLES

Application filed November 30, 1928. Serial No. 322,920.

The present invention relates to bridles for horses and has for its principal object to provide a blind for a bridle which is adapted to be constructed integrally with the cheek strap 5 of the bridle whereby to produce a strong article of this character and in which the time and labor involved in the construction or manufacture thereof is considerably lessened and the cost of manufacture substantially reduced.

The invention comprises essentially the construction of the cheek strap and blind integrally whereby to avoid the usual practice of making these parts of separate and distinct pieces of material and sewing the same together during the construction of the bridle.

Other objects and advantages reside in the special construction, combination and arrangement of the various elements forming the invention as more fully hereinafter described and claimed, reference being had to the accompanying drawings forming part hereof, wherein like numerals refer to like parts throughout, and in which:

Figure 1 is a perspective view of one form of the combined blind and cheek strap,

Figure 2 is a rear edge elevational view,

Figure 3 is a side elevational view of a modified form of the invention, and

Figure 4 is a rear edge elevational view thereof.

Referring now to the drawing in detail, wherein for the purpose of illustration I have disclosed the preferred embodiment of my invention, and with particular reference to Figures 1 and 2, and the numeral 5 designates a bridle blind of usual shape to one edge of which is formed the vertically extending strap 6.

The blind 5 and cheek strap are cut from a single piece of material, such as leather and are usually formed of two or more coextensive laminations secured to each other by stitching 7 whereby to provide the suitable thickness in the material.

The upper end of the cheek strap 6 is concaved from its forward to its rear edge, as shown at 8 whereby to form a seat and for the lower edge of a harness ring 9 (shown

in dotted lines), secured in position by a strap 10, also shown in dotted lines, which extends longitudinally at opposite sides of the cheek strap 6 and having its end 11 secured in any suitable manner.

The strap 10 is secured throughout its length to the cheek strap by a double row of stitching 12. In the form of the invention shown in Figures 1 and 2, the lower end of the strap is formed with a forwardly disposed extension 13, said extension protruding downwardly below the horizontal plane of the lower edge of the strap 6, the lower end of the strap 6 and the rear end of the extension 13 also having their edges concaved or curved circularly as shown at 14 to provide a seat for a lower harness ring 15, said harness ring being secured also by the strap 10.

A nose strap 16 also extends through the ring 15 at opposite sides of the extension 13 and is directed forwardly thereof for extending across the nose of the animal.

The nose strap 16 is also secured to the extension 13 by a double row of stitching 17. In the modified form of the invention illustrated in Figures 3 and 4 of the drawings, the lower harness ring 15 is displaced by a square shaped ring 18 and the extension 13 as heretofore disclosed is dispensed with, the lower end of the cheek strap 6 being cut straight across for abutting one side of the ring 18.

The retaining strap 10 and the nose strap 16 are secured to the angular portion of the ring 18, as shown by the dotted lines in Figure 3.

It will be apparent from the foregoing that by forming the blind 5 integrally with the cheek strap 6 that the piecing of sections of the strap at the upper and lower ends of the cheek strap is thus eliminated in order to provide the extensions at the upper and lower ends of said strap for attaching the rings 9 and 15 respectively thereto for use in a manner well known in the art.

The harness constructed in accordance with my invention will accordingly be stronger as there is no danger of the pieces of the strap becoming separated through the breaking of the thread and furthermore the time required

for constructing the harness is materially reduced.

It is obvious that my invention is susceptible to various changes and modifications in construction without departing from the spirit of the invention or the scope of the appended claims, and I accordingly claim all such forms of the device to which I am entitled.

10 Having thus described my invention, what I claim as new is:

1. In a blind construction for bridles, a cheek strap formed integrally with the blind with its opposite ends terminating above and below said blind, said blind and said cheek strap being formed of a plurality of laminations whereby to add rigidity thereto, harness rings arranged at the upper and lower ends of said cheek strap, and a ring retaining strap 20 inserted through said rings and extended longitudinally at opposite sides of the cheek strap and secured throughout its length thereto.

2. A blind for bridles comprising a blinker 25 portion having integral strap portions extending laterally from opposite sides thereof to provide a cheek strap, one of said strap portions being provided at its outer end with an offset extension disposed forwardly and 30 outwardly of its outer end, each of said strap portions having a concaved ring seat at its outer end, and the said extension having the concaved seat forming a continuation of the adjacent ring seat of the strap, said offset extension 35 providing means for attachment to the nose strap, rings seated in the said ring seats, and a retaining strap embracing the said strap portions clamped longitudinally at opposite sides thereof, and extending 40 through the said rings, said retaining strap being secured to the said strap portions.

In testimony whereof I affix my signature.
ISAAC W. BROWN.
